CLAIM

The ornamental design for a writing instrument, as shown and described.

DESCRIPTION

FIG. 1 is perspective view as seen from the top, front and right side of a writing instrument showing our new design with the cap covering the writing point;

FIG. 2 is a front elevational view thereof;

FIG. 3 is a right side elevational view thereof where the left side view is a mirror image;

FIG. 4 is a rear elevational view thereof;

FIG. 5 is a top elevational view thereof;

FIG. 6 is a bottom elevational view thereof;

FIG. 7 is a perspective view as seen from the top, front and right side of said writing instrument with the writing point exposed and the cap repositioned over the bottom of the barrel;

FIG. 8 is a front elevational view thereof;

FIG. 9 is a right side elevational view thereof where the left side view is a mirror image;

FIG. 10 is a rear elevational view thereof;

FIG. 11 is a top elevational view thereof; and,

FIG. 12 is a bottom elevational view thereof.
